UNITED STATES PATENT OFFICE.

LARS GUNSTEIN WAHL, OF OSLO, NORWAY.

ARRANGEMENT FOR WEIGHING GOODS IN A HANGING POSITION.

Application filed February 18, 1926, Serial No. 89,153, and in Norway February 19, 1925.

The present invention relates to an arrangement for weighing goods in a hanging position, and the invention is specially adapted to be used in connection with lifting-cranes, derricks and the like, whereby it is possible to weigh the goods, while hanging in the hoisting apparatus.

The invention is substantially characterized by the fact, that a locking member is fastened to a hoisting-wire or to a part connected with the same, which locking member cooperates with a supporting member, suspended by a scale-wire, so that the goods after a certain lifting and following lowering are automatically transferred from the hoisting-wire to the scale-wire.

The invention is illustrated in the accompanying drawings, in which:

Figure 1 shows the invention in connection with a derrick, seen perspective.

Figure 2 shows the arrangement for transferring the goods from the hoisting-wire to the scale-wire, in vertical section.

Figure 3 shows the same, partly in section on the line A—A in Figure 2.

Figure 4 is a plan view of Figure 2.

Figure 5 shows a detail.

—1— indicates a mast, to which is pivotally mounted a boom —2—. A hoisting-wire —3—, coming from a windlass, not shown, in known manner runs over a lead block —4— and through the middle run of a tripartite tackle block —5— and ends in a hoisting hook —6—. —7— indicates a wire, which is in one end connected with a scale —8— of some known construction. The wire —7— is led over a lead block —9— and in the other end it is fastened to a chock —10—. From said chock two wires —11— and —12— are running, which are led through the outer runs of the tripartite block —5—, and from the end of which a supporting member —13— is suspended, cooperating with a locking member —14— on the hoisting-wire —3—.

The supporting member —13—, which is shown in a larger scale in the Figures 2, 3 and 4, consists of an upper casing, joined of two parts —15— and —15'—, enclosing the hoisting wire —3— so that this one runs freely through the same. The upper part of the casing is furnished with bolt-holes —16— for screwing together the two parts of the casing and for fastening hooks (not shown) to be suspended by the wires —11— and —12—.

The lower part of the casing bears two shafts

—17— and —17'—, both of which carry a loosely mounted arm —18— resp. —18'—. In the lower parts of these arms, which are forked (Figure 3), a lever —19— resp. —19'— is pivotally mounted, which is at the inner end formed with an upright semi-cylindrical collar —20— resp. —20'—. At the outer end the levers are formed with a knot —21— resp. —21'— supporting the lower end of a rod —22— resp. —22'—, which is loosely mounted in a slot on the back of the arms —18— resp. —18'—. To the middle part of the shafts —17— and —17'— plate-members —23— resp. —23'— are fastened, lying in a socket in the arms —18— resp. —18'—. To the ends of the shafts —17— and —17'— cranks —24— resp. —24'— are fastened between which a spiral spring —25— resp. —25'— is stretched, which normally owing to the position of the cranks proportionate to the center line of the shafts —17— and —17'— forces the plate-members —23— and —23'— against the upper edge of the rods —22— resp. —22'— and thereby keeps the arms —18— and —18'— pushed together, so that the parts —19— resp. —19'—, pivotally mounted on the same, with the collars —20— resp. —20'— touch each other. The plate-members —23— and —23'— are by a link —26— resp. —26'— connected with a disc —27— resp. —27'—, pivotally mounted on a pin —28— resp. —28'— in the casing member —15— resp. —15'—. When the springs —25— and —25'—, are lying above the center line of the shafts —17— and —17'—, as hereafter further explained, the surface of the plate-members —23— and —23'— will engage with an edge —29— resp. —29'— in the socket of the arms —18— resp. —18'—.

The lower end of the hoisting-wire —3— is fastened to a ring —30—, running freely in a tubular part —31— to the lower end of which the hoisting hook —6— is fastened. In the upper end of the tube —31—, whose diameter is somewhat smaller than the inner diameter of the ring-shaped casing formed by the collars —20— and —20'—, is fastened a conical locking member —14— with a collar —33— turned downwards and inwards, intended to co-operate with the collars —20— and —20'—, as hereafter further explained. To the hoisting-wire —3— a little above the locking member —14— is fastened a conical part —34—, intended to

co-operate with the discs —27— and —27'—.

The arrangement operates in the following manner:

Suppose that some goods are hanging in the hook —6— with the parts in the position shown in Figure 1, the locking member —14— will during the lifting touch the levers —19— and —19'— and push the same from each other, as they are permitted to swing somewhat about their taps in the arms —18— resp. —18'—, which arms at the same time are swinging outwards about the shafts —17— resp. —17'— and thus permitting the locking member —14— to pass. Then the lifting is stopped and by influence of the springs —25— and —25'—, which are pressing the plate-members —23— and —23'— downwards, the arms —18— and —18'— will be led back, and the parts will get the position shown in Figure 2.

If now the hoisting-wire —3— is lowered, the locking member —14— as well as the goods will be suspended by the levers —19— and —19'—, and as the hoisting-wire runs freely through a central hole in the locking member —14— and may be further lowered together with the ring —30—, loosely placed in the tube —31—, the goods will in this way be quite released from the hoisting-wire and now be carried by the scale wire —7—, by which the supporting member —13— is hanging by means of the wires —11— and —12—. The pointer of the scale —8— will now indicate the weight of the goods weighed.

At the same time as the locking member —14— with the goods is suspended by the levers —19— and —19'—, the latter will swing about the taps and displace the rods —22— resp. —22'— upwards, with the result that the plate-members —23— resp. —23'—, being in touch with the same and being fastened to the shafts —17— resp. —17'—, will turn the shafts so much that the springs —25— and —25'— will be lying above the center line of the shafts. With the springs in this position, the plate-members —23— and —23'— are kept with their upper surface pressed against the edges —29— resp. —29'— in the socket of the arms —18— resp. —18'—, whereby the said arms now try to move away from each other, what is however prevented, because the collar —33— on the locking member —14— clutches the collar —20— and —20'— on the levers —19— resp. —19'—. At the same time as the plate-members —23— and —23'— swing upwards, the discs —27— and —27'—, connected with the plate-members by the links —26— resp. —26'—, will swing somewhat against the hoisting-wire —3—. When after the weighing has taken place, the goods shall again be transferred to the hoisting-wire, this one is hauled till the locking member —14— with the collar —33— has got clear of the collar —20— and —20'—

on the levers —19— resp. —19'—. On account of the position of the springs —25— and —25'— above the center lines of the shafts —17— and —17'—, the arms —18— and —18'— will now swing outwards and permit the locking member —14— to pass. At the same time as the arms are swinging outwards, the discs —27— and —27'— will be further swung against the hoisting-wire —3— and take such a position, that the conical part —34— during the downward movement of the hoisting-wire will touch the opposite edges of the discs, and force the same outwards with the result, that the shafts —17— and —17'— swing back, so that the springs —25— and —25'— are again coming below the center line of the shafts, whereby the effect of the springs will now be such, that the arms —18— and —18'— are again moving into their starting position with the collars —20— and —20'— in touch against each other and with the locking member —14— hanging below the same.

The performance of the invention shown in the drawing is only stated as an example, as alterations may be made by the same without departing from the scope of the invention.

What I claim is:

1. An arrangement for weighing goods in a hanging position including in combination, a supporting member embodying spring pressed grippers, a scale wire for suspending the grippers, a hoisting wire and a locking member in operable connection with the hoisting wire for cooperating with the spring pressed grippers in such manner that after a certain lifting movement by the hoisting wire the load is released so that the locking member will settle upon the grippers to effect weighing of the load and after the load is weighed the locking member is raised in order to be disengaged from the grippers while the latter automatically spring open to allow the hoisting wire to again take the load.

2. An arrangement for weighing goods in a hanging position including in combination, a supporting member, a scale wire for supporting the suspending lever the supporting member including arms pivotally mounted therein, springs for pressing the arms toward each other, collars at the lower ends of the arms, a hoisting wire movable through the supporting member, and a conical locking member carried with the hoisting wire and which during the lifting movement is forced between the arms and during the following lowering movement is suspended from the collars.

3. An arrangement for weighing goods in a hanging position as claimed in claim 2, wherein shafts are provided for swingably suspending the arms, cranks on said shafts to which the springs are connected so as to normally keep the arms pushed together, and

when the goods are suspended by the arms are automatically transferred to such a position that when the goods are again released from the arms, the arms will again swing outwards and permit the locking member to pass freely.

4. In an arrangement for weighing goods in a hanging position in combination, a hoisting wire, a locking member carried thereby, a scale wire and a supporting member suspended by the scale wire and through which the hoisting wire is movable, opposed shafts in the supporting member, cranks on the ends of the shafts, opposed arms pivotally suspended from the shafts, springs connected to the cranks, levers pivoted to the lower ends of the arms, semi-circular collars formed on the adjacent inner ends of the levers, stops on the outer ends of the levers, rods slidably supported on the arms and resting against the stops, and plate members fastened to the shafts and normally in touch with the rods in such a manner that when the locking member with the goods is suspended by the levers the rods will be moved upwards and thereby bring the springs above the center line of the shafts.

5. In an arrangement for weighing goods in a hanging position as claimed in claim 4, wherein a stop member is fastened to the hoisting wire above the locking member and wherein revolving discs are arranged in the supporting member, links for connecting the revolving discs with the plate members so that during the outward swinging movement of the arms the discs are brought in such a position that during the lowering of the goods, when the weighing has taken place, they swing back owing to the engagement thereof by the stop member whereby the springs are led back to their normal positions below the center line of the shafts.

6. An arrangement for weighing goods in a hanging position as claimed in claim 4, wherein means is provided for connecting the hoisting wire with the locking member and the hoisting hook firmly connected to the same so that it can be entirely released from the said parts when weighing takes place.

In testimony whereof I have signed my name to this specification.

LARS GUNSTEIN WAHL.
